BINDER

George S. Emery, Tulsa, Okla.

Application August 24, 1935, Serial No. 37,735

5 Claims. (Cl. 129—1)

This invention relates to loose leaf binders and more particularly to binders of the type in which provision is made for varying their capacity.

An important object of the invention is to provide a binder of what may be termed the double-post unit type in which the posts are adapted to be extended in height to provide for the accumulation of sheets in the binder, the invention in its preferred form contemplating the provision of a plurality of cylindrical post sections threadedly connected together and variable as to height by rotation of one member within another.

Another object of the invention is to provide a binder in which the companion posts of each double-post binding unit are united by an arcuate connector, one end of the connector being resiliently mounted in one of the posts, so as to permit the connector to be raised against spring tension, and the other end of the connector having an axial projection or pilot adapted to seat, upon the release of the connector, in a socket carried upon the end of the other post. By this arrangement the connector may be readily disengaged from the latter post and swung to out-of-the-way position to allow the convenient association or disassociation of perforated sheets with the post, and then reengaged with the pilot maintained in the socket of the post by spring pressure so as to avoid accidental displacement therefrom.

The invention has as another object to provide, in a binder of the expandable type having a bottom and a top cover connected to a back member, which serves to protect the rear edges of the stack of bound sheets, means for increasing the width of the back member from time to time in correspondence with variations in the height of the stack of contained sheets due to the accumulation of sheets in the binder or to withdrawals therefrom. More particularly this object is accomplished in the preferred form of my invention by hingedly connecting the bottom and top covers to a back member composed of a plurality of rigid complementary sections arranged to be detachably connected at or adjacent their longitudinal edges and permitting the insertion of supplementary sections to expand the width of the back. The sections may be advantageously united edge-to-edge by a tight frictional tongue-and-groove fit, a suitable number of supplemental sections being provided to allow widening the back member to an extent corresponding to the full capacity of the binder as determined by the adjustability afforded by the binding posts.

55 An alternative form of back member within

the scope of my invention contemplates forming the back of a plurality of rigid relatively shiftable sections, and providing means for retaining the sections in their different positions of adjustment.

Still another object of my invention is to provide a binder having top and bottom covers of rigid construction which are extensible in a lengthwise direction to adapt the binder to the accommodation of sheets of different lengths and thus fully protect the edges of the sheets which would otherwise project beyond the lower end of the binder. According to the preferred form of the invention, the covers are composed of a plurality of transverse sections having a sliding 15 interfit one with another in a manner such that one cover section may be separated or closed together lengthwise with respect to an adjacent section to vary the dimensions of the covers.

Other objects and advantages of the invention will become apparent from the following detailed description of typical binder constructions embodying the novel features of my invention, reference being had to the annexed drawing in which:

Figure 1 is a perspective view of a binder of the double-post unit type constructed in accordance with the principles of the invention;

Figure 2 is a detail view, in part sectional, of one of the double-post units;

Figure 3 is fragmentary cross-sectional view through the bottom cover along the line 3—3 of Fig. 1;

Figure 4 is a detailed perspective view of one end of a multisection back member showing the 35 sections separated; and

Figure 5 is a perspective view of an alternative form of back which may be employed with the binder of Fig. 1.

The binder illustrated in Fig. 1 comprises a flat bottom cover 20 and a flat top cover 21 (one end only being shown), made of rigid material such as pulpboard, having their ends hinged to a multipart back member 22 also of rigid material. The covers are of substantially identical 40 construction and mounted upon the bottom cover adjacent its rear transverse edge are a plurality of double-post units 23 arranged in parallel intermediate the side margins of the cover, and each comprising two posts 24 and 25 spaced a 45 short distance apart lengthwise of the cover and joined at their tops by an arcuate shaped connector 25a.

As best shown in Fig. 2, the two posts of each unit are constructed exactly alike. The post 24

consists of a stud 26 which is oppositely threaded upon its two ends and is provided with an enlarged circumferential ring 27 intermediate its length. One end of the stud projects through an opening 28 formed through the bottom cover and projects a sufficient distance beyond the lower surface of this cover to allow a nut 29 to be mounted upon its extended end, so that by tightening this nut the cover is firmly clamped against the ring 27.

To the end of the stud which projects above the upper surface of the cover is connected a relatively short cylindrical sleeve 30 having a smooth circumference and its upper end being beveled inwardly as indicated at 31. The sleeve 30 is internally threaded throughout its length and arranged to travel along this thread is a second cylindrical sleeve 32. The sleeve 32 is of approximately the same length as sleeve 30 and is 20 of smaller diameter than the latter so as to be snugly received within the latter. Upon the lower end of sleeve 32 is fixedly mounted an annulus 32a which is exteriorly threaded so as to cooperate with the threads upon the interior of sleeve 30 whereby by rotating sleeve 32 with the fingers the sleeve is moved inwardly or outwardly of sleeve 30 and toward or from the upper end of stud 26 which closes the bottom of the latter sleeve. The circumference of sleeve 32 is, similar to sleeve 30, smooth surfaced and beveled inwardly at its elevated end as indicated at 33.

As has already been stated post 25 is of exactly the same construction as post 24, corresponding parts being indicated by the same reference numerals. The double-post unit thus is composed of a plurality of telescopic sleeves having a smooth circumference and of slightly different diameter which taper together to facilitate the passage of perforated sheets along the posts.

The two posts 24 and 25 of each double-post unit are joined at their tops by the arcuate shaped connector 25a which carries upon one end a hollow stem 35, having an annulus 36 fixed upon its lower end threaded to engage the screw threads 45 upon the interior of sleeve 32 and having a cap 37 threadedly secured to the stem 35 and closing its upper end. The connector is maintained in association with the cap 37 and stem 35 by means of a pin 38 which is threaded into the bottom 50 face of the connector at one end and which passes through an opening in the cap 37. The other end of the pin 38 is provided with a circular head 40 which snugly fits within the inside of stem 35 and presents a bearing surface for one end of a spring 41 which surrounds the pin and is under light compression between the head and the cap. By rotating the pin the tension of the spring may be varied. The cap has a down turned flange 42 which is interiorly threaded to engage threads 60 upon the upper end of the stem 35 in the assembly of the parts.

The other end of the connector is provided with an axially disposed cylindrical pilot 45 which slips into a socket 46 formed in the upper end of a short plug 47 which is formed with an exteriorly screw threaded boss at its lower end so as to engage the threads upon the interior of sleeve 32 of post 25.

It will be apparent from the construction just described that in order to place perforated sheets upon or remove them from the post 25, it is only necessary to raise the connector 25a against the action of spring 41 a sufficient distance to lift pilot 45 out of socket 46 and the connector may 75 then be rotated to out-of-the-way position as

indicated in dotted lines in Fig. 1. To reengage the connector, it is again raised and swung back into alignment with the post 25 and the pilot dropped back into the socket 46. The spring 41 5 yieldingly holds the connector in place. Apertures 49 are advantageously provided in the walls of the screw threaded parts of the unit for engagement with a pin (not shown) to facilitate turning should the parts stick.

As sheets accumulate in the binder and the 10 stack (indicated by dotted lines in Fig. 1) increases in height the pair of posts of the two double-post units of the binder may be extended by rotating sleeves 32 within sleeves 31, stem 35 within sleeve 32 on post 24 and plug 47 within 15 sleeve 32 on post 25. Thus a large amplitude of movement of the posts is afforded and the binder can perform the duty of several binders of the older type, at the same time having the advantage of compactness when it is used for accommodating only a small volume of material.

The bottom and top covers 20 and 21 are of substantially counterpart construction except for the provision of longitudinal slots 50 in the top cover which provide clearances for the upper 25 ends of the double-post units, and since these units may be erected at different distances apart upon the bottom cover the slots will be sufficient in number and suitably located to anticipate changes in the locations of the double-post units. 30

As sheets are added to the binder and the posts are extended, the back member 22 must be widened to keep pace with the increasing height of the stack of bound sheets. This is accomplished by the following construction. The top 35 and bottom covers are connected to the back member by means of spaced projections 55 formed on the end of the covers interfitting between correspondingly spaced projections 56 carried upon the longitudinal edges of end strips 57 40 and 58 and having pintles 59 passing through, aligned recesses extending through the projections, as shown in Fig. 1, to hinge the covers to the end strips. The end strip 57 has formed upon its edge opposite to that carrying the projections 45 and 58 a tongue 60, and the end strip 58 has formed in its edge opposed to the tongue 60 a recess 61 capable of receiving the tongue and frictionally retaining the two end strips together. Supplemental strips 62 provided with tongues 63 and 50 recesses 64 upon their opposite edges, corresponding to the tongue and recess of the end strips are adapted to be inserted intermediate the end strips in the manner best indicated in Fig. 4 so as to build up the back in small increments. 55 While it is contemplated that these strips will be held together with sufficient firmness by means of the binding fit between the tongues and grooves, if desirable screws (not shown) may be passed through openings between these parts to 60 positively retain them in association.

Both the bottom and top covers are made up of a plurality of separable transverse sections, the three sections A, B and C composing the bottom cover 20 corresponding in all respects to 65 the three transverse sections composing the top cover 21. As shown in Fig. 1 the end section A of the bottom cover is hinged to the back member 22 while the intermediate section B is provided at its opposite edges with tongues 65 which 70 snugly fit within complementary grooves 66 formed in the adjacent edges of end sections A and C. As will be apparent from this construction, the sections may be separated in a lengthwise manner, the tongues 65 sliding within the 75

grooves 66, to lengthen the top and bottom covers and thus completely protecting the longest sheets that may be contained in the binder.

So as to positively retain the sections in their positions of adjustment, screws 68 having enlarged heads (Fig. 3) are passed through openings 70 in the end sections A and C aligned with openings 71 in the tongues, and these screws are held in place by sleeve nuts 12. To permit a nice adjustment of the covers to be obtained a plurality of openings 70 are provided in each end section aligned in a direction lengthwise of the covers so as to allow any one of these openings to be brought into registry with the complementary openings 71 in the tongues 65 of the intermediate section.

A modified form of extensible back member is illustrated in Fig. 5. Secured to the bottom and top covers 20 and 21 are flat, sheet metal inserts 75, these inserts each carrying spaced cylindrical projections 76 upon their longitudinal margins which extend beyond the end of the cover. These projections fit into the spaces between complementary projections 77 carried upon the contiguous edge of a plate 78, suitable pintles 79 extending through the eyes of the projections and hinging the metal inserts and plates together.

The plates 78 which are connected to companion inserts overlie each other for a substantial distance upon their longitudinal margins opposite to the margins carrying the projections 77 and are held together by means of releasable screws 80 passing through elongated slots 81 formed in the overlapped plates. The arrangement is such that by unloosening the set screw the plates may be shifted relative to each other to widen or narrow the back. To one of the plates 78 may be attached an index or label support 82. It will be apparent that various other changes in arrangement and design may be made in the binder constructions described above, which are to be regarded as exemplary only of preferred forms which the invention may take, without departing from the spirit of my invention.

I claim:

1. A loose leaf binder comprising a bottom cover composed of a plurality of transverse sections, binding posts supported upon the cover, and means uniting the transverse sections to permit separation of the sections in a direction lengthwise of the cover.

2. A loose leaf binder comprising a bottom cover composed of a plurality of transverse sections, binding posts supported upon the cover,

a tongue-and-slot connection between adjacent sections whereby one of the sections may be shifted relative to the other, and means for maintaining said sections in their different adjusted positions.

3. In a loose leaf binder, a double-post binder unit comprising a pair of upright posts, each post including a plurality of sleeves of appreciable length but of different diameters and each sleeve being interiorly threaded for the major portion of its length, one of said sleeves having an enlarged screw-threaded circumferential portion adjacent one of its ends adapted to cooperate with the internal threads of an adjacent sleeve permitting the first-mentioned sleeve to be rotatably telescoped within the latter sleeve, an arcuate-shaped connector bridging the upper ends of said pair of posts, and a swivel connection joining one end of said connector to one of said posts so as to permit the other end of the connector to be swung into and out of alignment with the other post.

4. In a loose leaf binder, a double-post binder unit comprising a pair of upright posts, each post including a plurality of sleeves of approximately the same length but of different diameters and each sleeve being interiorly threaded for the major portion of its length, one of said sleeves having an enlarged screw-threaded circumferential portion adjacent one of its ends adapted to cooperate with the internal threads of an adjacent sleeve permitting the former sleeve to be rotatably telescoped within the latter sleeve, an arcuate-shaped connector bridging the upper ends of said pair of posts, a swivel connection joining one end of said connector to one of said posts so as to permit the other end of the connector to be swung into and out of alignment with the other post, and spring means for yieldingly holding the ends of said connector in engagement with the posts.

5. A loose leaf binder comprising a bottom cover, a pair of binding posts supported upon the bottom cover adjacent one of its ends, said bottom cover being composed of a plurality of transverse sections, a tongue upon the transverse edge of one of said sections engageable within a slot in the opposed transverse edge of an adjacent section to permit of slidably adjusting one section relative to another, and a clamping screw supported upon the last-mentioned section engageable in an opening provided in the tongue of the first-mentioned section.

GEORGE S. EMERY. 55
